UNITED STATES PATENT OFFICE.

PETER L. FRY, OF LULING, TEXAS.

PLOW STANDARD.

Application filed August 12, 1921. Serial No. 491,736.

To all whom it may concern:

Be it known that PETER L. FRY, a citizen of the United States of America, residing at Luling, in the county of Caldwell and 5 State of Texas, has invented new and useful Improvements in Plow Standards, of which the following is a specification.

The object of the invention is to provide a simple, inexpensive and efficient plow 10 standard adapted for attachment with facility to the beam and having bracing means which are related with the means of attachment of the plow handles; and with this object in view the invention consists in a 15 construction and combination of parts of which a preferred embodiment is shown in the accompanying drawings, wherein:—

Figure 1 is a perspective view of a plow foot embodying the invention applied in the 20 operative position to the plow beam.

Figure 2 is a vertical sectional view on the plane indicated by the line 2—2 of Figure 1.

Figure 3 is a horizontal section on the 25 planes indicated by the line 3—3 of Figure 1.

The beam 10 is provided with a down-turned rear end 11 extended rearwardly to form the drag 12, and secured by a bolt 13 or its equivalent to the down turned end are 30 the clips 14 which carry the plow handles 15'.

The plow standard 15 consists of parallel co-extensive bars spaced apart at an interval corresponding with the thickness of the 35 beam and arranged respectively at opposite sides of and in contact therewith while a link 16 arranged in the plane of the beam and therefore between the planes of the members of the standard is secured to the 40 latter at its front end by a transverse bolt 17 and at its rear end is arranged in bearing engagement with the front edge or surface of the down turned rear end, and preferably is located between the extremities of the 45 clip members 14 to which it is secured by a transverse bolt 18. The upper portion of

the standard is secured to the beam by means of a clamp 19 having spaced plates connected by transverse bolts 20.

In the adjustment of the standard it will 50 be obvious that it is simply necessary to loosen the clamp whereupon the standard may be varied in position angularly and in depth by a movement limited only by the link 16 which by reason of its terminal connection respectively with the standard and the clip on the down turned rear end is capable of a swinging movement.

The rearward pressure on the plow standard incident to the operation of the tilling 60 or soil working bit of whatever type may be employed and attached to the standard is conveyed by the latter through the link to the beam, said link occupying a position substantially in the path or line of strain 65 and being transversely braced by its engagement between the parallel members respectively of the standard and clip.

Having described the invention, what is 70 claimed as new and useful is:—

A plow comprising a longitudinally curved beam, clips pivoted to the opposite surfaces of the beam and at the curved portion thereof, said clip having parallel lower portions which are disposed beyond the side 75 surfaces of the beam, a link pivoted between the lower parallel portions of the clips and having an end portion which bears against the adjacent edge of the beam, a standard pivoted to the lower edge of the link, means 80 for clamping the upper portion of the standard to the beam, and handles mounted upon the clips, the parts being so arranged that the link serves as a brace between the lower portion of the standard and the intermediate portion of the beam, whereby the handles are relieved of vibration transmitted from the standard to the beam.

In testimony whereof he affixes his signature.

PETER L. FRY.
